HIGH-FREQUENCY ELECTRICAL FILTER
FOR USE IN WAVE GUIDESHenri Gutton and Antoine Jean Ortusi, Paris,
France, assignors to Compagnie Generale De
Telegraphie Sans Fil, a corporation of FranceApplication April 11, 1947, Serial No. 740,844
In France June 2, 1945Section 1, Public Law 690, August 8, 1946
Patent expires June 2, 1965

6 Claims. (Cl. 178—44)

1

This invention relates to high frequency electrical filters for use in wave guides and more particularly though not exclusively to band pass filters for use on decimetre waves in a wave guide employed, for example, for connecting a transmitter with a radiating horn. An arrangement in accordance with this invention comprises at least two resonators coupled in the guide by one or more spaces.

For a certain critical coupling given by a resonant space between two resonators the transmission curve of an assembly thus constituted presents a flat topped curve characteristic of a band pass filter.

An arrangement in accordance with this invention can, however, comprise more than two resonators inter-coupled by intervening adjustable spaces and be arranged to give a transmission curve of almost any form desired.

The specific description hereinafter given is limited for the sake of simplicity to the case of two identical coupled resonators but the invention is not limited to this case. The invention is illustrated in and further explained in connection with the accompanying drawings, in which

Figure 1 is a diagrammatic showing of the wave guide having two spaced cavity resonators;

Figure 1a is a view of the same wave guide partly in perspective and partly in section;

Figure 2 shows a transmission curve of each resonator taken alone;

Figure 3a to Figure 3d are diagrams of transmission curves based on varying relations of length of the resonator chambers and of the space therebetween;

Figure 4 is a view partly in diagram and partly in section of an adjustable metallic insert;

Figure 5 shows a typical curve connecting the length values of the resonator and the intervening space;

Figure 6 is a transverse sectional view of a sliding arrangement for the resonator chamber; and

Figure 7 is a longitudinal sectional view of the arrangement shown in Figure 6.

Referring to Fig. 1, R_1 and R_2 are two identical resonators formed with apertures F_1 , F'_1 and F_2 , F'_2 , and arranged in a wave guide C with an adjustable space E between them. Each resonator, considered alone, has a transmission curve of the form represented in Fig. 2, where co-efficients of transmission T are plotted as ordinates against frequency f . The width of the band passed by such a resonator may be re-

garded as the band Δf between the two frequencies at which the transmission co-efficient is $1/2$.

Theory and experience alike show that if the distance l (Fig. 1) between the two resonators

5 R_1 , R_2 is varied the form of the transmission curve for the whole arrangement (R_1 , E , R_2) also modifies gradually. For example, if the length l of the space E is the same as the length l_0 of each resonator, and is a whole multiple of the 10 half wave length $\lambda/2$ in the guide, the curve of transmission is of the form illustrated by Fig. 3a; if l is equal to

$$l_0 + \frac{\lambda}{20}$$

15 the curve of transmission is of the form illustrated in Fig. 3b; if l is substantially equal to

$$l_0 + \frac{\lambda}{10}$$

20 the curve of transmission is as represented by Fig. 3c; while for values of l notably greater than l_0 the curve of transmission reverts to a form as shown in Fig. 3d.

25 The case where $l=l_0$ is that of three like resonators arranged end to end and this case may be useful as a means for transmitting three equally separated frequencies. But the case with which the present invention is primarily concerned in practice is that corresponding to Fig. 30 3c, i. e. the band pass case.

In practice a band pass filter in accordance with this invention may be made and adjusted without touching the resonators R_1 and R_2 once positioned, for the length l may be, in effect, 35 varied (without actually moving R_1 or R_2) by providing one or more adjustable metallic inserts such as rods or screws V (Fig. 4) positioned with respect to the apertures F'_1 or F_2 of the resonators R_1 and R_2 at a distance equal to one quarter of the wave length λ in the guide. The effective length of the space is then a function of the extent of entry of the insert or inserts V and accordingly a desired modification of the transmission curve of the arrangement is obtainable by adjusting the said inserts. Fig. 5 is a typical curve connecting values of $l-l_0$ expressed in centimetres as a function of the extent of entry e (also expressed in centimetres) for a rectangular sectioned guide 5 cm. x 16 cm. operating on a wave length (λ) of 20 cm.

To facilitate adjustment of the resonators where movable resonators are required they may be constituted by suitably sectioned boxes (corresponding with the wave guide section) of dimension a little less than the interior dimensions

of the guide so that they can slide easily therein, electrical contact with the guide being ensured by suitable metallic contacts and handles sliding in longitudinal slots formed in the guide wall being provided. The metallic contacts should be located along nodal lines of the electric current circulating in the plane of the section of the guide. The regulating rod or other insert of each resonator is situated in a transverse plane different from that of the handles thereof and also slides freely in a wall slot formed in the guide.

Fig. 6 shows in transverse sectional view and Fig. 7 in longitudinal sectional view a sliding arrangement of the nature described in the last paragraph for the case of a rectangular guide dealing with an H_{01} wave. In these figures E represents a box which slides in the guide G between friction contacts Q, P, P' represent the handles fixed to E and which slide in longitudinal slots L in the walls of the guide G and V represents the tuning insert of the resonator.

What we claim is:

1. A filter device comprising, in the interior of a wave guide provided with longitudinal slots constructed in its wall, two cavity resonator elements positioned in series in said guide and tuned to the same frequency, one of said resonator elements comprising a box slideable in the interior of the guide and provided with contacts for establishing electrical contact with the guide and with handles extending out from the guide through said slots.

2. A filter device comprising, in the interior of a guide provided with longitudinal slots constructed in its walls, two cavity resonator elements positioned in series in said guide and tuned to the same frequency, one of said resonator elements comprising a box slideable in the interior of the guide and provided with contacts for establishing electrical contact with the guide and with handles extending out from the guide through said slots, a conductive rod positioned in the interior of said guide in the space between said resonators, and means connected to the

guide for adjusting the depth of entry of said rod into the guide.

3. A filter device according to claim 1 in which said cavity resonators are mutually positioned at a distance substantially equal to

$$l_0 - \frac{\lambda}{10}$$

l_0 being the length of one of said cavity resonators and λ being the length of the wave in the guide.

4. A filter device according to claim 2 in which said resonators are mutually positioned at a distance substantially equal to

$$l_0 - \frac{\lambda}{10}$$

l_0 being the length of one of said cavity resonators and λ being the length of a wave in the guide.

5. A band-pass filter device comprising, in the interior of a wave guide, two cavity resonator elements positioned in series in said guide and tuned to the same frequency, one of said resonator elements being a slideable element so as to vary the physical distance separating the two resonators from one another and to thereby adjust the width of the pass band of said filter.

6. A band-pass filter device as claimed in claim 5 including a conductive rod positioned in the interior of said guide in the space between said resonators, and means connected to the guide for adjusting the depth of entry of said rod into the guide.

HENRI GUTTON.
